LENA BENNETT, OF NEW YORK, N. Y.

DESIGN FOR A BADGE.

SPECIFICATION forming part of Design No. 34,771, dated July 16, 1901.

Application filed June 18, 1901. Serial No. 65,067. Term of patent 3½ years.

To all whom it may concern:

Be it known that I, LENA BENNETT, a citizen of the United States, and a resident of the city of New York, borough of Manhattan, in the 5 county and State of New York, have invented and produced a new and original Design for a Badge, of which the following is a specification, reference being had to the accompanying drawings, forming a part thereof, in 10 which—

Figure 1 is a front elevation of a badge embodying the features of my design, and Fig. 2 is a transverse section through the badge.

The leading features of the design consist 15 in the representation of a buffalo in action and a pan held by one foot of the animal.

The minor features of the design consist

of the convexed front and straight back of that portion of the badge representing a buffalo and in the handle for the pan and the 20 flag ornamentation at the bottom of the body of the pan.

Having thus described my invention, I claim as new and desire to secure by Letters Patent—

The design for a badge herein shown and described.

In testimony whereof I have signed my name to this specification in the presence of two subscribing witnesses.

LENA BENNETT.
